(57) CLAIM

The ornamental design for a tank for water closet, as shown and described.

DESCRIPTION

In a preferred embodiment, the nature of this product is as a plumbing fixture primarily useful as a reservoir for supplying water to a toilet bowl.

FIG. 1 is a left, top, front perspective view of a tank for water closet embodying my new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a bottom plan view thereof; and,

FIG. 7 is a rear elevational view thereof.

The broken line representations of a trip lever in FIGS. 1-4 and 6-7, and of holes in FIG. 6, are for the purpose of illustration only, and form no part of the claimed design.
